UNITED STATES PATENT OFFICE.

ALBERT S. DIXON, OF LOS ANGELES, CALIFORNIA, ASSIGNOR TO ASPHALT PAPER PIPE COMPANY, OF LOS ANGELES, CALIFORNIA, A CORPORATION OF CALIFORNIA.

ATOMIZER.

SPECIFICATION forming part of Letters Patent No. 752,529, dated February 16, 1904.

Application filed March 24, 1903. Serial No. 149,267. (No model.)

To all whom it may concern:

Be it known that I, ALBERT S. DIXON, a citizen of the United States, residing at Los Angeles, in the county of Los Angeles, State of California, have invented a new and useful Atomizer, of which the following is a specification.

My invention relates to atomizers designed for breaking up and atomizing liquids under the pressure of an expansive fluid, and more especially to such an atomizer designed for breaking up and atomizing thick or heavy hydrocarbons for fuel consumption.

The general object of the invention is to provide simple, cheap, durable, and positive means whereby thick or heavy hydrocarbons may be reduced to fuel and supplied in perfectly-regulated quantities to a fire-box of a furnace, so that the fire may be constantly maintained at any determined volume or force or may be varied, as desired.

A further object is to provide simple and effective means for preventing any clogging of sand or grit in heavy or thick hydrocarbons, such means consisting, preferably, in a rotary valve.

To these ends my invention consists generally in an atomizer having a body providing a closed cylindrical chamber provided with an oil or fuel inlet opening into said chamber axially, a plurality of inlets opening thereto tangentially and adapted to deliver expansive medium into said chamber, and an outlet and regulable means in alignment with said axial inlet and movable into said chamber toward said axial inlet for controlling the admission of oil or liquid fuel therethrough, and, further, in providing in said cylindrical chamber a rotary member, seated upon the bottom of said chamber and provided on its upper face with radiating flights forming open-sided open-ended channels or grooves, said tangential inlets adapted to communicate into the channels or grooves formed by said radiating flights, said rotary member provided with an axial hole or perforation registering with said axial inlet and through which said axial inlet communicates into the channels or grooves formed by said radiating flights.

My invention consists, further, in the constructions and in general and specific combinations of parts, all as hereinafter described, and particularly pointed out in the claims.

The invention will be more readily understood by reference to the accompanying drawings, forming a part of this specification, in which—

Figure I is a sectional plan view of an atomizer embodying my invention, the same being taken on the line I I of Fig. II. Fig. II is a sectional view on the line II II of Fig. I.

As shown in the drawings, my atomizer is composed of a body 2, preferably cylindrical in cross-section, and provided with an expansive-medium inlet 3, which opens into the channel 4, which substantially surrounds the outside of the wall 5' of the breaking and mixing chamber 5, which chamber, as shown, is cylindrical in cross-section, the wall of the outlet 6 forming the termination of the channel 4. From the channel 4 I provide tangential inlets 7 into the breaking and mixing chamber 5 through the wall thereof, as shown.

8 represents a rotary breaker and mixer which, as shown best in Fig. II, is provided with a portion 9, adapted to bear upon the boss or raised portion 10 in the bottom of the chamber 5.

11 represents a cover provided with an annular collar or flange 12, which is threaded and adapted to screw onto the cylindrical chamber 5 and engage the threaded portion of the wall 5' thereof. This cover is provided with a central opening or perforation which when the cover is in position comes opposite the axial inlet 13 into the chamber 5, and through this central opening in the cover a regulator 14 extends into the chamber and is threaded into the central perforation of the cover, so that its position may be readily adjusted. A suitable hand-wheel or other operating means 15 is provided on the outer end of this regulator.

16 represents a suitable packing.

17 represents a hexagonal head provided on the outside of the cover, by means of which it may be readily turned into position on the chamber or removed therefrom.

The rotary breaker and mixer 8 is free to revolve within the chamber 5 and rests of its own weight upon its seat 10.

While I have found that the atomization of thick or heavy hydrocarbons can be accomplished by a single inlet 7, yet I have found that a plurality of such tangential inlets suitably disposed in the wall 5' will balance the rotary breaker and mixer and prevent the same from frictional contact with any portion of the wall 5'. I therefore prefer to utilize a plurality of tangential inlets, as shown.

The rotary breaker and mixer consists of a circular disk slightly less in diameter than the 15 diameter of the chamber 5 and has a series of radiating flights 18 upon its upper face. The disk or flat portion of the rotary breaker and mixer is preferably thin, and the tangential inlets open above the surface thereof, so as to 20 communicate against the flights.

The oil enters the chamber 5 through the axial inlet 13 under pressure. The steam flowing through the inlet 3 into the channel 4 flows through the tangential inlets 7 against the 25 flights, revolving the rotary breaker and mixer, and the incoming oil is thereby thoroughly mixed with the expanded steam, and the revolution of the breaker atomizes it, and the atomized product flows out through the 30 outlet 6. The regulator 14, in connection with the central perforation of the rotary breaker and mixer 8, forms a rotating inlet for the oil, and any dirt or grit in the oil is ground up between the walls of the central perforation and the sides of the regulator, forming, 35 in effect, a rotating and self-clearing valve.

Having thus described my invention, I claim as new and desire to secure by Letters Patent—

1. In an atomizer, in combination a body 40 comprising a closed cylindrical chamber, provided with an inlet opening thereinto axially, a plurality of inlets opening thereinto tangentially, and an outlet, and means in alignment with said axial inlet movable into said chamber toward said axial inlet for regulating the admission therethrough.

2. In an atomizer in combination, a body 50 comprising a closed cylindrical chamber, provided with an inlet opening thereinto axially, a plurality of inlets opening thereinto tangentially and an outlet, a rotary breaker and mixer in said chamber provided with a series of flights against which said tangential inlets are adapted to deliver their stream, said 55 breaker and mixer provided with a central perforation, registering with said axial inlet, and means in alignment with said axial inlet and movable into said chamber toward said axial inlet for regulating the admission therethrough.

3. In an atomizer in combination a body 60 comprising a closed cylindrical chamber, provided with an inlet opening thereinto axially, an inlet opening thereinto tangentially and an 65 outlet, a rotary breaker and mixer seated on

the bottom of said chamber and provided with a central perforation, registering with said axial inlet and provided with a series of radiating flights on its face, and means in alignment with said axial inlet and movable into 70 said chamber toward said axial inlet for regulating admission therethrough.

4. In an atomizer, in combination, a body comprising a closed cylindrical chamber provided with an axial inlet, a tangential inlet and 75 an outlet, and with a seat for a rotary member, a rotary member loosely seated on said seat and provided with a central perforation registering with said axial inlet and with a series of flights upon its face, said flights forming open - sided, open - ended channels or 80 grooves, and means in alignment with said axial inlet and movable into said chamber toward said axial inlet for regulating the admission therethrough. 85

5. In an atomizer, in combination, a body comprising a closed cylindrical chamber, provided with an axial inlet, a plurality of tangential inlets and an outlet, and with a seat for a rotary member, a rotary member loosely seated 90 on said seat and provided with a central perforation registering with said axial inlet, and with a series of flights upon its face, said flights forming open-sided, open-ended channels or grooves, and means in alignment with said 95 axial inlet and movable into said chamber toward said axial inlet for regulating admission therethrough.

6. In an atomizer, the combination with a body comprising a breaking and mixing chamber, provided with an axial inlet, a tangential inlet and an outlet and with a seat for a rotary breaker, a rotary breaker mounted on 100 said seat and provided with a central perforation registering with said axial inlet and with flights upon its upper face. 105

7. In an atomizer, the combination with a body comprising a breaking and mixing chamber, provided with an axial inlet, a tangential inlet and an outlet and with a seat for a 110 rotary breaker, a rotary breaker mounted on said seat and provided with a central perforation registering with said axial inlet and with flights upon its upper face, and means mounted within said chamber for regulating the admission of fluid through said axial inlet. 115

8. In an atomizer, the combination with a body comprising a closed breaking and mixing chamber, provided with an axial inlet, a tangential inlet and an outlet, and provided 120 with a seat for a rotary breaker, and a rotary breaker seated on said seat and provided with a central perforation registering with said axial inlet and a regulator adapted to control the admission through said axial inlet and forming with said rotary breaker a self-clearing rotary valve. 125

9. In an atomizer, the combination of a body provided with an inlet for expansive medium and with a channel whereinto said inlet commu- 130

nicates, a closed cylindrical chamber formed within the inner wall of said channel, a plurality of tangential inlets communicating from said channel into said chamber, said body having an axial inlet into said chamber and a peripheral outlet therefrom.

10. In an atomizer, the combination of a body provided with an inlet for expansive medium and with a channel whereinto said inlet communicates, a closed cylindrical chamber formed within the inner wall of said channel, a plurality of tangential inlets communicating from said channel into said chamber, said body having an axial inlet into said chamber, and an outlet therefrom, and a rotary breaker and mixer in said chamber provided with a central perforation registering with said axial inlet, and with a series of flights upon its face.

15. In an atomizer, the combination of a body provided with an inlet for expansive medium and with a channel whereinto said inlet communicates, a closed cylindrical chamber formed within the inner wall of said channel, a plurality of tangential inlets communicating from said channel into said chamber, said body having an axial inlet into said chamber, and an outlet therefrom, and a rotary breaker and mixer in said chamber provided with a central perforation registering with said axial inlet, and with a series of flights upon its face, and a regulator operating in connection with the perforation through said rotary breaker and mixer and adapted to control the admission of liquid through said axial inlet.

20. In an atomizer, the combination of a body provided with an inlet for expansive medium and with a channel whereinto said inlet communicates, a closed cylindrical chamber formed within the inner wall of said channel, a plurality of tangential inlets communicating from said channel into said chamber, said body having an axial inlet into said chamber and an outlet therefrom, and means extending in axial alignment with said axial inlet whereby the admission therethrough may be controlled.

25. In an atomizer, in combination, a body provided with an expansive-medium inlet, a channel whereinto said inlet communicates, a closed cylindrical chamber formed within the inner wall of said chamber, said body provided with an inlet entering said body axially and with a plurality of tangential inlets opening from said channel into said chamber and an outlet from said chamber, said body provided with a seat within said chamber for a rotary breaker, a rotary breaker seated thereon, said rotary breaker provided with a central perforation registering with said axial inlet, and with a series of radiating flights extending out from said central perforation.

30. In an atomizer, in combination, a body provided with an expansive-medium inlet, a channel whereinto said inlet communicates, a closed cylindrical chamber formed within the inner wall of said chamber, said body provided

with an inlet entering said body axially and with a plurality of tangential inlets opening from said channel into said chamber and an outlet from said chamber, said body provided with a seat within said chamber for a rotary breaker, a rotary breaker seated thereon, said rotary breaker provided with a central perforation registering with said axial inlet, and with a series of radiating flights extending out from said central perforation, and a regulator extending into said chamber opposite said axial inlet and adapted to be moved with relation to said inlet to control the admission of liquid therethrough.

35. In an atomizer, in combination, a body comprising a closed cylindrical chamber, provided with an inlet opening thereinto axially, a plurality of inlets opening thereinto tangentially, and an outlet, a breaker and mixer within said chamber and adapted to rotation by the streams from said tangential inlet, and means in alignment with said axial inlet movable into said chamber toward said axial inlet for regulating the admission therethrough.

40. In an atomizer, the combination of a body provided with an inlet for expansive medium and with a channel whereinto said inlet communicates, a closed cylindrical chamber formed within the inner wall of said channel, a plurality of tangential inlets communicating from said channel into said chamber, said body having an axial inlet into said chamber and an outlet therefrom, and a rotary breaker and mixer in said chamber, adapted to be revolved by the streams from said tangential inlets.

45. In an atomizer, the combination, with a body provided with an inlet for expansive medium and with a channel whereinto said inlet communicates, a closed cylindrical chamber formed within the inner wall of said channel, a tangential inlet communicating from said channel into said chamber, said body provided with an axial inlet and a peripheral outlet.

50. In an atomizer, the combination, with a body provided with an inlet for expansive medium and with a channel whereinto said inlet communicates, a closed cylindrical chamber formed within the inner wall of said channel, a tangential inlet communicating from said channel into said chamber, said body provided with an axial inlet and an outlet, and a breaker and mixer in said chamber adapted to revolution by the stream from said tangential inlet.

55. The combination in an atomizer, of a body comprising a breaking and mixing chamber, of a breaker and mixer rotatably mounted therein and provided on its side with a series of open-sided channels or ways, an axial inlet port adapted to direct liquid into said channels, a tangential expansive - medium inlet adapted to direct its stream against the periphery of said breaker and mixer, and an outlet.

60. The combination, in an atomizer, of a body comprising a breaking and mixing chamber, of a breaker and mixer rotatably mounted

therein and provided on its side with a series of open-sided channels or ways radiating from the center, an axial liquid-inlet adapted to direct liquid into said channel, a tangential expansive-medium inlet adapted to direct its stream against the periphery of said breaker and mixer, an outlet, and means for regulating the flow of liquid through said liquid-inlet.

21. In an atomizer, the combination with a body provided with an inlet for expansive medium, and with a channel whereinto said inlet communicates, and a closed cylindrical chamber formed within the inner wall of said channel, a tangential inlet communicating from said channel into said chamber, said body provided with an axial inlet and an outlet, and means within said chamber forming a regulable rotary, self-clearing valve in connection with said axial inlet.

22. In an atomizer, the combination with a body provided with an inlet for expansive medium, and with a channel whereinto said inlet communicates, a closed cylindrical chamber formed within the inner wall of said channel, a tangential inlet communicating from said channel into said chamber, said chamber provided with an axial inlet and a peripheral outlet, and means within said chamber forming a regulable, rotary, self-clearing valve in connection with said axial inlet.

In testimony whereof I have hereunto set my hand, this 19th day of March, A. D. 1903, at Los Angeles, in the county of Los Angeles and State of California.

ALBERT S. DIXON.

In presence of—

FREDERICK S. LYON,
JULIA TOWNSEND.
